UNITED STATES PATENT OFFICE.

CHARLES C. SATTERWHITE, OF RICHMOND, VIRGINIA, ASSIGNOR, BY MESNE ASSIGNMENTS, TO THE DIAMOND CIGARETTE MACHINE COMPANY, OF WEST VIRGINIA.

CIGARETTE-MACHINE.

SPECIFICATION forming part of Letters Patent No. 583,002, dated May 18, 1897.

Application filed April 2, 1896. Serial No. 585,967. (No model.)

To all whom it may concern:

Be it known that I, CHARLES C. SATTERWHITE, a citizen of the United States, and a resident of Richmond, in the county of Henrico and State of Virginia, have invented certain new and useful Improvements in Cigarette-Machines; and I do declare the following to be a full, clear, and exact description of the invention, such as will enable others skilled in the art to which it appertains to make and use the same, reference being had to the accompanying drawings, and to letters and figures of reference marked thereon, which form a part of this specification.

Figure 1 is a plan view of a machine embodying the invention. Fig. 2 is a plan view of a portion of one of the cheesing-chains. Fig. 3 is a detail view, partly in section, showing the relative positions of the two chains at the beginning of the cheesing operation, the links which are shown being detached. Fig. 4 is a similar view showing the relative position of the chains at their opposite end portions where the cheesing is completed. Figs. 5 and 6 are detail perspective views showing the links of the respective chains. Fig. 7 is a plan view of the cutting mechanism with the frame in dotted lines. Fig. 8 is a side view of the same.

This invention has relation to that class of cigarette-machines wherein the tobacco is shaped into a continuous endwise-moving filler-rod which is subsequently wrapped in a ribbon of paper and finally cut into cigarettes; and it relates more particularly to the mechanism employed for shaping or "cheesing" the tobacco to form this continuous rod and also to the mechanism by which said rod after it has been wrapped is cut into cigarettes.

An object of this invention is to provide a cheesing mechanism of this character which can be relied upon to perform its work in a rapid, efficient, and satisfactory manner. It is designed, furthermore, to provide means for this work, all the parts of which move at a uniform speed, whereby the rod during its formation is relieved from the friction of stationary parts or surfaces by or over which it must travel and which might tend to check or impede its movements to such an extent

as not only to interfere with its continuity and regularity of formation, but also to endanger or prevent the satisfactory operations of the wrapping and cutting mechanisms simultaneously taking place upon advanced portions of the rod.

A further object is to provide cutting mechanism of simple character which is capable of doing its work rapidly and efficiently.

With these objects in view the invention consists in the novel construction and combination of parts, all substantially as hereinafter described, and pointed out in the appended claims.

Referring to the accompanying drawings, the letter Z designates the framework of a cigarette-machine.

A designates the feed mechanism, which may be of any suitable character—such, for instance, as shown in my pending application, Serial No. 541,911, filed March 15, 1895—and which is arranged to discharge the tobacco in proper condition between a pair of endless chains B B', which constitute the filler-forming mechanism. Said chains are mounted horizontally and longitudinally side by side upon a table Z' of the machine upon horizontal wheels or pulleys C C', the former of which have teeth or sprockets c, by means of which the chains are driven, while the latter form idle-carriers. The two driving-pulleys C, which are at the forward end portion of the chain, are journaled nearer together than the two pulleys C' at the rear, whereby the operative portions of said chains instead of being parallel are caused to gradually approach each other toward their front ends.

The chain B consists of a series of interpivoted links 1, each of which has a projecting portion 2, in the vertical edge of which is formed an open longitudinal horizontal groove 3. The chain B' also consists of a series of links 4, which are of somewhat similar character, but which are each formed with a projecting tongue 5, which is designed to loosely engage the grooves 3 of the opposing links in the manner best shown in Figs. 3 and 4. The longitudinal edge of the upper portions of the projection 2 of the links 1 are grooved or concaved, as indicated at 6, and the shoulders or

abutments at the inner ends of the tongues 5 at their upper side are similarly concaved or grooved, as indicated at 7.

The links of both chains are usually connected in the following manner: Every other link is formed with a thickened portion having therein a longitudinal horizontal groove 9 in its outer edge, which receives a reduced portion 10 of the link upon each side thereof, the pivots or pins 11 passing through the parts, as indicated. (See Figs. 5 and 6.) The ends of the portions 8 and 10 are rounded, as indicated, whereby they may move upon each other, and also to form recesses for the engagement of the sprockets or teeth of the driving-wheel C. (See Figs. 5 and 6.)

D D are the two idlers, which are adjustably journaled a short distance behind the said wheel C and which are for the purpose of pressing the operative portions of the chains toward each other. By a proper adjustment of these idlers the pressure of the chain upon the filler-rod can be accurately controlled.

E F are two idler-rollers which are placed transversely over the belts for the purpose of holding the rod down while it is being formed.

Both chains are designed to be driven at a perfectly uniform rate of speed by means of suitable gear connections W with the main driving-shaft X. The chains are at such distance apart at their rear portions that the tongues 5 at first just engage the grooves 3 of the opposing links, (see Fig. 3,) the two grooved edges 6 and 7 being therefore considerably separated from each other (usually about one inch) and form between them a trough to receive the tobacco as it falls from the feeding mechanism, the bottom of the trough being formed by the tongues 5, which in this position fit each other so closely as to form a practically continuous surface. This trough or conduit, however, is constantly narrowing as the tongues 5 come into deeper engagement with each other, until at the front end (see Fig. 4) the two grooved edges 6 and 7 come together around the rod and give it its cylindrical form. The links now begin to pass around the pulleys, opening away from the rod, which passes to the wrapping mechanism.

In Fig. 1 of the drawings I have shown the improvements applied to a machine of the general character described and claimed in my application above referred to, the letter Y indicating a short trough or guide through which the rod passes to the pair of grooved rolls G, where it enters upon the paper fed from the roll H.

I is the folding or wrapping mechanism, and J is the pasting device.

After the enveloped rod leaves the wrapping mechanism it passes to the improved cutting mechanism now to be described, as follows:

K designates a rotary disk carried by a shaft K' in a plane transverse to the move-

ment of the rod. Said disk has journaled therein at equal distances from each other and near its periphery a series (usually six) of short shafts K², which are parallel to and concentric with the shaft K'. Secured to each of the said shafts upon the front face of the disk is a cutter-holder L, which projects beyond the periphery and is formed with a shoulder l, which forms a seat for a thin knife M. Said knife has an oblique cutting edge, its front end or corner being nearer the axis of the disk than the rear end or corner by a distance about equal to the diameter of a cigarette, say three-eighths of an inch. Behind each of the shafts K²—that is, between it and the shaft K'—a cylindrical boss or lug N is secured to the face of the disk K, and seated upon this lug or boss is a tightly-coiled spring O, whose inner end portion is extended in one direction and has a bearing upon a pin or stud o of the disk, while its opposite end portion is extended to and engaged with the heel portion of the adjacent cutter-holder L, as indicated at l'. On each shaft K² is also a collar P, having a pin or projection P, which is a little behind the center of said shaft.

R is a stationary cam which is secured to the bed-plate of the machine and which is designed to be successively engaged by each of the pins or projections p during each revolution of the disk K a short time before the cut is made. In the drawings I have shown this cam as having a curved edge r, which at its lower portion is substantially concentric with the axis of K' and in such relation thereto that the pins or projections k come easily into engagement therewith in rotation. The said edge, however, gradually increases its eccentricity to the axis of shaft K', which it more nearly approaches, whereby as the said pin or projection moves along the same the collar will be turned backwardly, thereby drawing down the knife-holder against a pin or stop p' of the disk and putting the spring O under tension—that is to say, said spring is gradually being wound during the engagement of the pin or projection with said cam edge. Just as the knife comes to the rod said pin or projection suddenly escapes the point of the cam at R' and the spring at once unwinds, suddenly throwing the knife and the knife-holder upwardly and forwardly through the rod. It will be seen, therefore, that while the knife is being rotated by the disk it is at this time suddenly thrown upwardly and forwardly with a speed which exceeds that of its rotation. In making the cut the knife works against the face of a guide S, through the opening of which the rod is passing, and which holds the rod to the action of the knife. The disk K may be driven by means of a connection with the main driving-shaft X. In the present instance I have shown this connection as consisting of a transverse shaft T, driven by bevel-gear T' from the shaft X and geared to a parallel shaft T² above the bed-plate. The shaft K is connected by

bevel-gear T³ with the shaft K'. The gear is of such character that the disk K (when six cutters are employed) will make one revolution in the same time that the machine forms 5 and feeds thereto a length of rod equal to six cigarettes. Owing to the instantaneous manner in which the knives act, the mechanism exerts no retarding influence upon the continuous onward feed of the rod, and a 10 true and perfect cut is made.

I do not limit myself to the exact arrangement of the parts as herein shown and described, as the same may be varied without departing from the spirit and scope of my 15 invention.

I would also state that while the present improvements have been more especially designed for use upon a machine of the character described and claimed in my application 20 above referred to, they may nevertheless be adapted to other machines.

Having thus described my invention, what I claim as new, and desire to secure by Letters 25 Patent, is—

1. In a cigarette-machine, filler-rod-forming mechanism, comprising essentially a pair of endless chains whose operative portions gradually approach each other from their rear to their forward end portions, the links 30 comprising one chain having tongues and the links of the other chain having grooves arranged to be engaged by said tongues, said tongues forming the bottom of the conduit constituted by the chains, substantially as 35 specified.

2. In a filler-rod-forming mechanism for cigarette-machines, a pair of endless chains, the links of one of said chains having grooves therein, and the links of the other chain having 40 projecting portions adapted to engage the said grooves, and to form the bottom of the conduit formed by the operative portions of the said chains, all of said links having means for operating upon the tobacco as it 45 rests upon the said projections together with means for carrying and driving said chains, substantially as specified.

3. In a cigarette-machine, filler-rod-forming mechanism, comprising a pair of endless 50 chains supported horizontally, side by side, with their operative portions gradually approaching toward their front ends, and consisting each of a series of pivoted links, the links of one chain having grooved portions, 55 while the links of the other chain have tongues to engage said grooves, means for pressing the operative portions of said chains toward each other, and pressing devices above the chains, together with means for supporting and actuating said chains, substantially as specified.

4. In a cigarette-machine, a pair of endless chains arranged side by side and forming between them a filler-rod carrying and shaping conduit of gradually-decreasing width, the 65 bottom of said conduit being formed by one of said chains, substantially as specified.

5. In a cigarette-machine, the combination

of two endless chains placed side by side and consisting each of a series of pivoted links, the links of one chain having projecting portions formed with horizontal grooves in their vertical edges, while the links of the other chain have tongues arranged to engage with said grooves, the links of both chains also having opposing grooves or concaved faces, substantially as specified. 70 75

6. In a cigarette-machine, a pair of endless chains, constructed and supported to form between them a filler-rod carrying and forming conduit of gradually-decreasing width, and 80 consisting each of a series of links, having interfitted or rounded pivoted portions, the links of one chain also having projecting portions formed with a horizontal groove at their vertical edges, and the links of the other chain 85 having projecting tongues adapted to engage said grooves, and to form the bottom of said conduit, together with means for actuating said chains at a uniform speed, substantially as specified. 90

7. In a cigarette-machine, the combination with feeding mechanism, of a pair of endless chains arranged side by side, and forming between them a filler-rod supporting and forming conduit of gradually-decreasing width and 95 into the widest end portion of which the feeding mechanism is arranged to discharge, one of said chains having grooved links, and the other having projections arranged to engage said grooves and to form the bottom of said 100 conduit, together with wrapping, pasting and folding mechanisms through which the rod passes after leaving the said chains, substantially as specified.

8. In a cigarette-machine, cutting mechanism comprising a rotary carrier, a series of spring-actuated cutters pivoted thereto and capable of independent movement in the plane of rotation, and means for putting the actuating-springs under tension at the proper 110 time, and for suddenly releasing same, substantially as specified. 105

9. In a cigarette-machine, cutting mechanism comprising a rotary carrier mounted to rotate in a plane transverse to the feed of the 115 rod, a series of cutters carried thereby and free to move independently in the plane of their rotation, actuating-springs attached to said cutters and normally inactive, and means for putting said springs under tension and for 120 releasing the same at the proper time, substantially as specified.

10. In a cigarette-machine, cutting mechanism, comprising a rotary carrier mounted to rotate in a plane transverse to the feed of 125 the cigarette-rod, a series of equally-distant, peripherally-located cutter-holders pivoted to said carrier, the knives carried by said holders, the normally-inactive springs attached to said holders, and means for putting 130 said springs successively under tension and for successively releasing the same at the proper time, substantially as specified.

11. In a cigarette-machine, the cutting

mechanism comprising the rotary carrier, the series of equally-distant shafts journaled in the peripheral portion thereof, the knife-holders secured one to each of said shafts and having each a projection, the cutters carried thereby and having oblique cutting edges, the normally-inactive springs engaging said holders, and the stationary cam arranged to be engaged by projections of the said holders to put said springs under tension, substantially as specified.

12. In cutting mechanisms for cigarette-machines the combination with a rotary car-

rier, of a cutter pivoted thereto, and capable of an independent movement in the plane of rotation, together with means whereby said cutter is momentarily advanced at a speed in excess of the rotary movement of the carrier, substantially as specified.

In testimony whereof I affix my signature in presence of two witnesses.

CHARLES C. SATTERWHITE.
